UNITED STATES PATENT OFFICE.

COLE STICKLE, OF INDIANAPOLIS, INDIANA.

STEAM-TRAP.

1,256,275.

Specification of Letters Patent. Patented Feb. 12, 1918.

Application filed December 8, 1916. Serial No. 135,771.

To all whom it may concern:

Be it known that I, COLE STICKLE, a citizen of the United States, and a resident of Indianapolis, county of Marion, and State 5 of Indiana, have invented a certain new and useful Steam-Trap; and I do hereby declare that the following is a full, clear, and exact description thereof, reference being had to the accompanying drawings, in which like 10 letters refer to like parts.

The object of this invention is to improve and simplify the construction and operation of automatic vacuum valve mechanism for radiators, steam heaters and the like.

15 One feature of the invention consists in so arranging the parts of the device as to make it symmetrical, smooth surfaced, and compact.

Devices of this kind heretofore have had 20 parts projecting considerably over the body of the device to a position which rendered them annoying in handling them and to users, and also unsymmetrical and ugly.

25 Since these devices are used at residences and offices on radiators, this feature of the invention is of considerable importance and is attained herein by substituting for the upper portion of the steam trap heretofore employed, a flat top suitably chambered as 30 herein set forth and providing in the wall of the body of the device, a suitable passageway communicating with the chamber in the top.

Another feature of the invention consists 35 in so chambering such top that the chamber therein will always register with the passageway in communication with the same for the escape of air from said tube in any position assumed by the top while screwing 40 it in place.

In other words, the top is so chambered that it is unnecessary in screwing it into place to stop it at any certain position. All that is required is to screw it down tightly. In 45 devices of this kind heretofore the parts had to be carefully adjusted to cause them to register with each other so as to operate. Hence it has been necessary heretofore to bolt or otherwise secure the top in only one 50 fixed position and it could not be screwed on.

Another feature of the invention consists in providing the top with an annular chamber near the external periphery of the top and in communication with a port which is 55 controlled by the float actuated valve, so that the chamber in the top can immediately

and directly connect with a discharge passageway leading to an outlet at the bottom of the device, while heretofore the discharge outlet has been located on the side of the 60 device where it was in the way and the vacuum pipe connected with it was also in the way.

The full nature of this invention will be understood from the accompanying drawings and the following description and claims:

In the drawing Figure 1, is a central vertical section through the device. Fig. 2 is a horizontal section on line 2—2 of Fig. 1. 70 Fig. 3, is a horizontal section on line 3—3 of Fig. 1.

There is shown in the drawings a cup-shaped vessel or casing 10, closed at its lower end and open at its upper end and internally threaded at 11 in its upper end and the top 12 has an annular flange 13 extending centrally and downwardly therefrom so as to screw into the top of the casing 10, with the outwardly extending portion of the top fitted tightly upon the top of the wall of the vessel 10. There is a nut 13' extending centrally upward from the top 12 whereby a wrench can be applied for tightening and releasing the top on the 80 vessel.

The inlet port 14 is integral with the side of the vessel 10 and from the inlet port a passageway 15 leads up to an inlet port 16 discharging into the upper portion of the 90 vessel 10 and into the chamber 17 in said vessel or casing.

The discharge outlet 18 is below the vessel 10 and integral therewith and in communication with a discharge passageway 19 95 leading from the top down the outer side of the vessel 10. The top 12 has an annular chamber 20 near its outer periphery and located so that it is always in communication with the discharge passageway 19, regardless of just how the top may be positioned when screwed down upon the vessel 10. The annular chamber 20 in the top is in connection with a central chamber 21 in the top through two oppositely located 100 openings 22 and 23. There is also a central opening 24 in the bottom of the top 12 through a downward extending annular collar 25 centrally located, as seen in Fig. 1. Into this collar there is screwed a sleeve 26 110 with an outwardly extending packing ring on it adapted to abut against the bottom of

the collar. A valve seat 27 is screwed into the upper portion of the sleeve 26 so as to lie within the opening 24 in the bottom of the top 12. This valve seat has a central 5 port 28 communicating with the central chamber 21 in the top 12.

Within the vessel 10 there is the usual bucket-shaped float 30 arranged to extend slightly above the bottom of the port inlet 10. 16. The usual valve stem 31 is secured centrally to the bottom of this float so that its lower end will rest upon a lug 32 in the bottom of the vessel 10 and its upper end would extend upward through the float and 15 above the top thereof to a point near the top of the vessel 10. The upper end of the valve stem 31 is tapered to form a valve 33 adapted when the float rises to engage the valve seat 27 and close the port 28. The 20 valve has a groove 37 in it for the escape of air.

The valve stem is held and guided by cross pieces 34 extending across the tube 35 the upper end of which is screwed on and is 25 supported by the sleeve 26, and the tube extends downward almost to the bottom of the float. There is an air port 36 through the tube 35 just above the top of the float when it is down.

30 In operation, as the condensation water enters through the inlet, it will gradually fill the chamber 17 of the vessel 10, and when the water rises high enough in the vessel 10, it will cause the float to rise and close the 35 port 28 leading to the chamber in the top of the device.

As the vessel fills the air will escape through air port 36 and groove 37 in valve 40 33 into the top chamber 21, port 23, chamber 20, passageway 19 and discharge outlet 18. After the water accumulates in chamber 17 sufficiently it will overflow into the float and when enough water has entered the float, the float will descend and open the port 28.

45 The invention claimed is:

1. A vacuum valve mechanism for radiators and the like including a vessel having a condensation chamber with the upper end open, a top adapted to screw thereon having 50 an inlet port centrally located and an annular chamber in communication with said port, a discharge passageway in said vessel in communication with the annular chamber in said top regardless of the angular position of the top, and a float controlled valve within the device for controlling the port in the top thereof.

2. A vacuum valve mechanism for radiators and the like including a vessel having a 60 condensation chamber therein with the upper end open, a top adapted to screw on the upper end of the vessel with an inlet port centrally located in it and an annular cham-

ber in communication with said port, and a discharge passage extending down on the 65 outside of said vessel and discharging below the vessel and with the upper end of said passage in communication with the annular chamber in the top regardless of the angular position of the top, and a float controlled 70 valve for closing the port in the top.

3. A vacuum valve mechanism for radiators and the like including a vessel having a condensation chamber open at its upper end and internally threaded at its upper end, a 75 top with an annular downwardly extending threaded flange adapted to screw into the top of said vessel, said top having an inlet port centrally located and a horizontal chamber in communication with said port 80 and an annular chamber surrounding and in communication with said horizontal chamber, a discharge passage at the side of said vessel in communication at its upper end with said annular chamber in the top regardless 85 of the angular position of the top, and a float controlled valve for closing the port in the top.

4. A vacuum valve mechanism for radiators and the like including a vessel having a 90 condensation chamber open at the top, a flat top adapted to screw in position for closing the upper end of said vessel, said top having an inlet port centrally located and a horizontal chamber in communication with 95 said port and an annular chamber surrounding and in communication with said horizontal chamber, a discharge passage at the side of said vessel in communication at its upper end with said annular chamber in the top 100 regardless of the angular position of the top, and a float controlled valve for closing the port in the top.

5. A vacuum valve mechanism for radiators and the like including a vessel having a 105 condensation chamber open at its upper end and having an integral vertical extension at one side thereof with a water inlet passage from the lower part of said extension to the upper part of said chamber, and said vessel 110 also having a vertical extension on the side thereof, with a discharge passageway therethrough arranged to discharge below said vessel, a top adapted to screw on said vessel for closing its upper end and having an inlet port centrally located and an annular chamber in communication with said port and extending over and in communication 115 with the upper end of the discharge passage regardless of the angular position of the top, and a float controlled valve for closing said port.

In witness whereof I have hereunto affixed my signature.

COLE STICKLE.
